UNITED STATES PATENT OFFICE.

SAMUEL J. GOLDSMITH, OF CHICAGO, ILLINOIS.

SKIRT-HANGER.

SPECIFICATION forming part of Letters Patent No. 754,763, dated March 15, 1904.

Application filed November 27 1903. Serial No. 182,776. (No model.)

To all whom it may concern:

Be it known that I, SAMUEL J. GOLDSMITH, a citizen of the United States, residing at Chicago, in the county of Cook and State of Illinois, have invented new and useful Improvements in Skirt-Hangers, of which the following is a specification.

This invention relates particularly to hangers upon which garments are hung or displayed for storage or other purposes, and has for its object to produce an improved device of that kind particularly serviceable in hanging dress-skirts.

The article is illustrated in the accompanying drawings, in which—

Figure 1 is a side view. Fig. 2 is a cross-section.

Referring specifically to the drawings, the ordinary curved wooden cross or shoulder bar is indicated at 6, and an attachment added by me consists of a clamp comprising two spring-arms 7, preferably formed of wire, which fork or extend from a hook 8, to which the desired rigidity is given by twisting the wires. At the ends the arms have oppositely-disposed buttons 9, between which the skirt or other garment is clamped when the article is in use. The arms extend loosely through vertical openings 10, made in the middle of the wooden bar, and these holes converge slightly toward the top of the bar, so that when the arms are pulled up through the holes they are brought toward each other and when they are shoved down they are spread apart.

In use in hanging a skirt the ends of the cross-bar are inserted under the opposite sides of the waistband, and at the middle the waistband is brought up between the buttons 9. Then by pulling up on the hook 8 or equivalent, shoving down the bar, the arms and but-

tons are forced together, forming a clamp upon the skirt, which when the hanger is hung prevents the sag of the skirt in the middle, ordinarily incident to hanging from two opposite points of the skirt-band.

45

The clamp is practically self-acting, inasmuch as if the skirt be placed between the arms thereof and the device hung on a nail by the hook the weight of the garment will pull the cross-bar down and bring the arms of the clamp together. To release the skirt from the clamp, the bar is shoved up, which spreads the arms and opens the clamp, so that the skirt may be removed. The hanger herein described will serve to keep skirts in shape, especially 55 heavy ones. The device is capable of a variety of other uses. Thus, for instance, the bar may be used to support one garment and the clamp to support another.

What I claim as new, and desire to secure 60 by Letters Patent, is—

1. A garment-hanger comprising a garment-supporting cross-bar, and a clamp between the ends of the bar having arms extending through the middle of the bar and terminating in a hook 65 above the same.

2. A garment-hanger comprising a garment-supporting cross-bar having openings diverging downwardly through the middle thereof, and opposite clamp members between the ends 70 of the bar and slidably through the openings and terminating in a hook above the same.

In testimony whereof I have signed my name to this specification in the presence of two subscribing witnesses.

SAMUEL J. GOLDSMITH.
